PAIR OF BINOCULARS

Kurt Jensen, Wetzlar, Germany, assignor to Ernst Leitz
G. m. b. H., Wetzlar (Lahn), Germany, a corporation of Germany

Application February 8, 1956, Serial No. 40,081

Term of patent 14 years

(Cl. D57—1)

Fig. 1

Fig. 1 is a front elevational view of a pair of binoculars, showing my new design;

Fig. 2 is a perspective view thereof, taken from an oblique angle to the rear of the pair of binoculars; and

Fig. 3 is a top plan view thereof.

I claim:

The ornamental design for a pair of binoculars, as shown.
